WALL-MOUNTED WIRING DEVICE

Gerald L. Swartwood, Monroe, Conn., assignor to The Bryant Electric Company, a corporation of Connecticut

Filed May 23, 1960, Ser. No. 60,704

Term of patent 14 years

(Cl. D26—13)

Fig. 1.

Fig. 2.

Fig. 3.

FIGURE 1 is a top plan view of a wall-mounted wiring device, showing my new design;

FIG. 2 is a bottom plan view thereof; and

FIG. 3 is a perspective view thereof.

The essential features of my design are shown in full lines, whereby spaced generally longitudinal grooves, connected by a lateral slot, delineate spaced attachment ears.

I claim:

The ornamental design for a wall-mounted wiring device, substantially as shown and described.
